UNITED STATES PATENT OFFICE

FRANZ PUENING, OF O'HARA TOWNSHIP, ALLEGHENY COUNTY, PENNSYLVANIA, AS-
SIGNOR TO THE KOPPERS COMPANY, A CORPORATION OF DELAWARE

COKE-OVEN APPARATUS

Application filed May 4, 1927. Serial No. 188,849.

My invention relates to coke oven apparatus and particularly to the provision of larry cars or charging trucks, having effective means for controlling the openings of a coking chamber during the charging operation.

My invention has for one of its objects to provide a seal for the charging openings of coking chambers that shall constitute a pressure-relief device therefor.

10 A second object of my invention is to provide a seal for the charging openings of coking chambers that shall be carried by the charging truck and selectively controlled therefrom.

15 A further object of my invention is to provide a seal of the character described that shall effectually prevent the loss of gases from the coking chamber during the charging operation, but that shall yield readily to 20 excessive pressure therein to prevent damage to the walls thereof in case of explosion.

In the charging of coke ovens and particularly when preheated coal is used in the manufacture of coke, gases in considerable volume are generated very quickly upon the entrance of the coal into the coking chamber. If sufficient air is present, an explosive mixture may be formed that will be ignited by the hot walls of the coking chamber.

25 Larry cars, as at present constructed, are provided with extensible sleeves for connecting the hoppers to the corresponding charging openings of the coking chamber. When the sleeves are in position and the gates of the 30 hoppers are closed, the gates constitute substantially rigid seals for the respective openings. In case of an explosion, the walls of the coking chamber are likely to be damaged.

When the sleeves are not extended or the 35 gates are open, smoke and gases may escape from the coking chamber either directly into the atmosphere or through the hoppers, since the means for normally withdrawing the smoke and gases is not sufficient to maintain pressure at or below atmospheric pressure at all of the openings simultaneously.

It is highly desirable not only to prevent the loss of gases with their valuable constituent vapors but to insure that such ex-

plosions as may occur do not damage the walls of the coking chamber.

To this end, I provide seals for the charging openings of a coke oven whereby the respective openings may be selectively opened or closed in such manner that the desired pressure may be maintained during the charging operation and all of the gases withdrawn from the coking chamber. 55

The seals are relatively light in weight 60 and readily movable outwardly to constitute pressure-relief devices in case of excessive pressure or an explosion in the chamber.

In the accompanying drawings—

Figure 1 is an end view in elevation of a 65 larry car constructed in accordance with my invention, parts being broken away;

Fig. 2 is a side view in elevation of the larry car of Fig. 1, parts being broken away, and a portion of a coke oven being shown in section; 70

Fig. 3 is a plan view of the larry car;

Fig. 4 is a view similar to Fig. 1 of a modification; and

Fig. 5 is an enlarged sectional view of a 75 second modification.

Referring particularly to Figs. 1, 2 and 3, a battery of coke ovens comprises individual coking chambers 11 only the tops of certain of which are shown. Each chamber has a 80 series of charging openings 12 that are normally closed by the usual relatively heavy lids or covers (not shown).

As shown in Fig. 2, each chamber is provided with a gas off-take pipe 13 by means of 85 which forced draft may be applied to the chamber, a steam jet (not shown) being employed for the latter purpose in the usual arrangement. The pipe 13 is provided with a pressure-relief device 14.

The ovens are charged by means of a larry car 15 that operates on tracks 16 that extend across the tops of the ovens. The larry car may accordingly be moved into position for charging any chamber through the series of 95 openings 12.

The larry car 15 comprises a frame 17 of structural iron or steel having wheels 18. It is provided with four hoppers 19, 20, 21 and 22 corresponding in number and in dis- 100

position to the openings 12 in each chamber 11. A cab 23 contains the several operating mechanisms for controlling the operation of the car and particularly the discharging of the coal from the hoppers.

5 Each hopper is provided with a chute 24 that is adapted to discharge directly downwardly into its corresponding opening. Each hopper has a gate 25 that is controlled 10 by a link mechanism 26 and an operating lever 27 located in the cab.

Beneath each chute 24 is a plate 28 having 15 arms 29 extending upwardly on either side of the chute. The arms 29 of all of the plates 28 are connected to rocker arms 31 secured to a rock shaft 32. The shaft 32 is controlled by an operating lever 33 connected thereto by a link mechanism 34. Each plate 28 has an 20 aperture 35 corresponding in size and shape 25 to the openings 12.

Each of the apertured members 28 carries loosely thereon a slidable valve plate 37 of relatively light weight for controlling the aperture 35. Each valve plate 37 is controlled 25 as to its horizontal position by a link 38, an arm 39 and an operating lever 40 that is operatively connected to the arm 39.

In the operation of the car 15, it may be assumed that the hoppers are filled with coal 30 which has preferably been preheated and that the car is in position to charge the heated coking chamber, the openings 12 of which are below the chutes of the corresponding hoppers. It may be assumed also that the 35 usual lids or covers have been removed from the openings 12. The lever 33 is actuated to the left from its illustrated position in Fig. 1 to the dotted-line position to lower the rocker arms 31 and the connected apertured 40 members 28 and valve plates 37. The openings 12 are now covered by the valve plates 37.

The operator may now empty the hoppers in any desired order. The discharge of the 45 hopper 22 shown in Fig. 1 will be described by way of example. The operator actuates the lever 40 to draw the plate valve 37 to its extreme left-hand position indicated by dotted lines to uncover the opening 12. The 50 lever 27 is then operated to open the gate 25 and the coal in the hopper passes through the chute 24, the aperture 35 and the opening 12 into the coking chamber.

When the coal enters the heated chamber, 55 gases are quickly generated in considerable quantities but the forced draft of the off-take pipe and the inrush of coal from the hopper are normally sufficient to prevent loss of gases through the openings. If, however, an explosion occurs, the valve plates 37 over the remaining openings yield readily 60 by reason of their light weight and loose mounting to relieve the pressure within the chamber and thus prevent damage to its 65 walls.

Inasmuch as the valve plates are pivotally connected to the respective operating links and their outward movement is limited by the lower ends of the chutes 24, they drop back substantially immediately after an explosion to cover the openings and prevent further loss of gases. The valve plate of the hopper being discharged is returned to its closed position immediately the hopper is 70 empty.

75 The operation of discharging the remaining hoppers is similar to that described, the valve plate of the desired hopper being opened for the discharge while the other valve plates are closed. The closed valve plates act as pressure-relief devices as previously set forth.

When all of the hoppers have been discharged, the lever 33 is returned to its full-line position to cause the rocker arms to raise 80 the apertured members 28 with their valve plates 37 from the openings 12 into their full-line positions adjacent to the lower ends of the chutes 24. The usual lids or covers are then placed over the openings 12. The car 85 15 may then be returned to be refilled, the gates 25 being closed at any desired time.

90 Referring now to Fig. 4, the structure shown therein differs from that of Figs. 1, 2 and 3, principally in the construction of the controlling mechanism for the valve plate. Each of the several valve plates 42 is rigidly connected to a relatively light rod 43 that is pivotally connected to a rocker arm 44, the latter being operatively connected to a lever 95 45.

95 Each valve plate 42 is controlled as to its vertical position by a flexible member such, for example, as a chain 46 that is connected to a rocker arm 47, the latter being operatively connected to a common operating lever 48.

In operation, the valve plates 42 are lowered into position by the lever 48 to seal 100 their corresponding openings. One of the valve plates 42 is shown in its sealing position in Fig. 4. The openings 12 are selectively uncovered by actuating the corresponding lever 45 to draw the valve plate 42 to the left about the outer end of the rocker 110 arm 47 as a pivot. The outer position of the valve plate 42 shown in Fig. 4 is indicated by dotted lines.

115 The hoppers are emptied in any desired order, the valve plates being selectively controlled by the operator to permit the coal to enter the openings 12. The openings are sealed except as coal is being emptied there-through. In case of explosion, the valve plates 42 move upwardly with the rods 43 about the end of the arm 44 as a pivot. The valve plates drop back into operative position to again seal the corresponding openings.

120 The seal shown in Fig. 5 differs from those 130

previously described in that it consists of an extensible sleeve 50 of light material surrounding the chute 24 and that may be raised or lowered by a suitable operating lever operatively connected to chains 51. The lower portion of the sleeve is provided with a horizontal extension 52 having a flange 53 for engaging the top of the oven to space the extension 52 therefrom.

10. Each of the sleeves 50 is provided with its individual operating lever and they may accordingly be selectively controlled to seal the openings 12. In case of an explosion, the sleeves, which are relatively light in weight, 15 yield upwardly as in the case of the valve plates to relieve the pressure in the coking chamber.

It will be noted that I have provided a charging truck having means for effectively 20 sealing the openings of a coking chamber during the charging operation. The sealing means may be selectively controlled by the operator whereby the hoppers may be emptied in any desired sequence or simultaneously, as desired. The seals constitute pressure-relief devices that avoid damage in case of an explosion.

The foregoing and other advantages will be apparent to those skilled in the art relating to coke ovens.

I claim as my invention:

1. A charging truck for coke ovens comprising a plurality of hoppers adapted to be connected to corresponding openings in a coking chamber to be charged and means carried by said truck for selectively controlling said openings, said means being yieldable to pressure within said chamber.

2. A charging truck for coke ovens comprising a plurality of hoppers adapted to be connected to corresponding openings in a coking chamber to be charged and closure devices for selectively controlling said openings, said closure devices being carried by said truck and yieldable to pressure within said chamber.

3. A charging truck for coke ovens comprising a plurality of hoppers adapted to be connected to corresponding openings in a coking chamber to be charged, closure devices for said openings carried by said truck, said closure devices being readily yieldable to pressure within said chamber, and means carried by said truck for selectively controlling said closure devices.

4. A charging truck for coke ovens comprising a plurality of hoppers adapted to be connected to corresponding openings in a coking chamber to be charged and means for controlling the communication between the hoppers and the respective openings comprising a member that is readily responsive to pressure within the chamber.

5. A charging truck for coke ovens comprising a plurality of hoppers adapted to be

connected to corresponding openings in a coking chamber to be charged and means for controlling the communication between the hoppers and the respective openings comprising a valve member normally preventing communication between the atmosphere and said chamber but that is responsive to pressure within said chamber to constitute a relief device therefor.

6. A charging truck for coke ovens comprising a plurality of hoppers for connection to a coking chamber to be charged, said chamber having a plurality of openings, and means readily yieldable to pressure within said chamber for selectively closing said openings whereby said hoppers may be successively discharged into said chamber substantially without loss of gases therefrom.

7. A charging truck for coke ovens comprising a plurality of hoppers adapted to be connected to corresponding openings in a coking chamber to be charged, closure devices for said openings carried by said truck, said devices being relatively light in weight and movable upwardly to constitute pressure-relief devices for said chamber but normally preventing communication between the atmosphere and said chamber, and means for selectively controlling said closure devices.

8. In a coke oven, the combination with a coking chamber having a plurality of recharging openings, of means for recharging said chamber through said openings, and means for selectively applying pressure-relief valves to said openings for preventing admission of air therethrough.

9. In a coke oven, the combination with a coking chamber having a plurality of charging openings, of means for charging said chamber through said openings, pressure-relief valves for said openings carried by said charging means, and means for selectively controlling the application of said valves to said openings.

10. In a coke oven, the combination with a coking chamber having a plurality of charging openings, of means for charging said chamber through said openings, means for selectively sealing said openings, said sealing means being readily operable to relieve excessive pressure within said chamber, and means carried by said charging means for controlling said sealing means.

In testimony whereof, I have hereunto subscribed my name this 3rd day of May, 1927.

FRANZ PUENING.
